Primary Examiner — Darlington Ly

(57) **CLAIM**

The ornamental design for a bicycle frame insert, as shown and described.

DESCRIPTION

This application is related to U.S. Design patent application Ser. Nos. 29/491,777, titled “Saddle with Grips,” and 29/491,778, titled “Bicycle with Integrated Accessories,” both of which are concurrently filed.

FIG. 1 is a top view of a frame insert showing my new design;

FIG. 2 is a bottom view thereof;

FIG. 3 is a left view thereof;

FIG. 4 is right view thereof;

FIG. 5 is a rear view thereof;

FIG. 6 is a front view thereof;

FIG. 7 is a bottom, front, and left-side perspective view thereof;

FIG. 8 is a top, rear and left-side perspective view thereof;

FIG. 9 is a top, front and right-side perspective view thereof; and,

FIG. 10 is a bottom, rear and right-side perspective view thereof.

The broken lines in the drawings illustrate portions of the bicycle frame insert that forms no part of the claimed design.

1 Claim, 5 Drawing Sheets
